UNITED STATES PATENT OFFICE.

ERNEST BRISTOW LE MARE, OF ST. HELENS, ENGLAND, ASSIGNOR TO PILKINGTON BROTHERS LIMITED, OF ST. HELENS, LANCASTER, ENGLAND, A BRITISH COMPANY.

PROCESS OF AND APPARATUS FOR ROLLING GLASS.

Application filed February 23, 1924, Serial No. 694,708, and in Great Britain March 2, 1923.

This invention relates to apparatus for rolling a strip of glass from molten glass issuing from a tank or other source, and has for its object to provide an improved construction of apparatus whereby the resultant glass is of better quality and more free from defects than has been that heretofore produced by known apparatus of the same type.

According to this invention, the molten glass flows along a chute or other conduit and forms a pool of molten metal in the approach to the pass of a rolling apparatus, that is to say, in the V-shaped space bounded by the two members of the rolling apparatus.

15 The strip of glass issuing from the pass of the rolling apparatus, passes over a flat stationary bed and then into a lehr where it is supported on rollers which are turned at a peripheral speed slightly in excess of the speed at which the strip issues from the pass, so that the strip is subjected to a small tractive effort from its point of issue from the pass.

In the accompanying drawings, Figure 1 25 is a vertical section of the apparatus, including part of the lehr and partly broken way, and Figure 2 is a part plan view showing a portion of the mouth of the chute and the rolling apparatus.

30 Referring to the drawings, molten glass 1 in a tank of which 4 is the front wall, issues through an opening 2 provided with gate 3 into a chute 5 to form a pool 6 in the approach to the pass of the rolling apparatus constituted by the two rollers 7 and 8, which latter, for convenience, are herein-after termed "pass rollers".

The chute 5 is provided with side walls 9, one of which only, is shown in Figure 2, and a crown 10 into which latter, at its upper front portion, heating gases are introduced by blow pipes 11. The crown 10 has an inner curved portion 12 by which the heating gases are deflected downwards on 45 to the stream of glass in the chute, and, as indicated by the arrows in Figure 1, pass along the stream issuing from the mouth of the chute. These heating gases are for the purpose of heating the chute 5 and crown 50 10 at the start of the process, and are not generally required when the process has reached normal working conditions.

The sides 9 of the chute 5 are, however, preferably heated during the normal working of the apparatus, and for this purpose

they are formed with passages 13 into which gases are introduced by blow pipes 11.

Alternatively, the inner sides of the chute 5 and the glass close to them, may be heated by gases from blow pipes so located as to direct the gases on to those sides and the glass adjacent thereto.

A slab 14 of fireclay or the like, is supported by a chain and balance weight 21 at the mouth of the chute 5, in such manner as to admit of it being adjusted in guides 22. The slab 14 may be in contact with the pool 6 and then has the function of controlling the arc of contact between it and the pass roller 7.

The glass strip 15 issues from the pass of the rollers 7, 8 and passes on to a stationary bed 16, 23, and from this into the lehr 17 in which the strip is supported on rollers 18. The stationary bed, in the constructional form shown in the drawings, comprises a curved portion 23 over which the glass passes on leaving the pass rollers 7, 8, as well as a flat portion 16 which supports the glass between the said curved portion and the lehr 17. For convenience of description of the arrangement illustrated, the two portions 16, 23 are hereinafter referred to as separate beds, 16 as a flat bed, and 23 as a curved bed.

The rollers 18 are rotated at a peripheral speed which is slightly in excess of the speed at which the strip issues from the rolling apparatus, so that the strip is subjected to a small tractive effort from its point of issue from the pass rollers 7, 8 up to the rollers 18.

The said tractive effort is sufficient to draw the strip over the flat bed 16 and also to draw it in a curve from the pass of the rolling apparatus on to the said bed.

The curved bed 23 is interposed between the lower roller 8 and the adjacent end of the flat bed 16, and may be integral with the latter, but is preferably independent thereof and formed of metal, and water-cooled.

In normal working, the tractive effort on the strip 15 is sufficient to keep the latter just clear of the curved bed 23 as shown in Figure 1, but this bed serves to support the strip at the start of the process and also during any possible irregularities in the normal working.

The length of the flat bed 16 and the cooling to which the strip is subjected while

2
passing over it, are of great importance to the working of the apparatus.

These two factors, which are to some extent interdependent, are so determined or regulated that the strip, on leaving the flat bed 16, has become "set", that is to say, has become sufficiently solidified on its surfaces to resist deformation when passing over the rollers 18, even though the interior of the strip may still be plastic.

The purpose of the flat bed 16 is to enable the strip 15 to assume a flat form by reason of its own weight, and for this reason the back end of this bed is located as close as is conveniently possible to the rolling apparatus, so that the strip is as plastic as possible while on the bed, and the said bed is of such a total length that the strip has time to assume a flat form before it passes off therefrom.

20 It will be understood that the flat bed 16 can serve this purpose only so long as the strip 15 remains sufficiently plastic and that therefore the length which can usefully be given to it, depends on the rate at which this strip, while on the bed, is allowed to cool.

It is preferred to provide means whereby this rate of cooling may be controlled and, in the form of apparatus shown in the drawings, the means provided for the purpose consist in a hood 19 extending over a portion of the flat bed 16, and the open back end of which has a vertically adjustable door 20, adapted to be held in any position, so that that end of the hood 19 may be closed to any desired extent. Heating gases may be introduced into the hood 19, if it be found necessary still further to retard the rate of cooling of the strip.

40 The source from which molten glass is supplied to the rolling apparatus may be a melting tank, or a refining chamber or forehearth; all such sources of molten glass are intended to be included in the word "tank" as used in this specification and claims.

45 The chute 5 is preferably of such length that the rolling apparatus may be situated at a convenient distance from the walls of the tank, but the said chute may be replaced by a short horizontal conduit or even a slot in the respective wall of the tank.

The rolling apparatus consists preferably in a pair of rollers of which, as shown in the drawings, the upper one (7) is in advance of the lower (8), so that that part of the surface of the roller 8 on which the pool 6 is formed, may have a downward inclination towards the pass. The two rollers may, however, be vertically one above the other and then the strip may issue horizontally from the pass and the curved bed 23 be omitted. Or, again, the two rollers 7, 8, may have their axes in the same horizontal plane.

60 The roller 8 which forms the lower surface of the strip, is preferably of larger diameter than is the other roller, and may be

replaced by a chain table of any known construction.

The flat bed 16 may be inclined downwards in the direction of travel of the glass, but such inclination must not be sufficient appreciably to diminish the effect of the weight of the strip in making that strip assume a flat form.

One or more rollers in the lehr 17, (such as the roller 24) may rest on the upper surface 75 of the strip above one or more of the rollers 18 forming the bed.

It is to be understood that the words "drawn" and "drawing" as used in this specification and claims are not employed in the technical sense indicative of the formation of the strip by drawing, although the tractive effort on the strip passing over the bed may result in a slight stretching of said strip.

Having described my invention, I declare 85 that what I claim and desire to secure by Letters Patent is:—

1. Process for producing a continuous strip of glass in which molten glass is rolled into a strip which is propelled by tractive 90 force applied to the strip only after it has "set" and the strip is supported before it has "set" in a flat and approximately horizontal position.

2. Process for producing a continuous 95 strip of glass in which molten glass issuing from a tank to form a pool, is rolled into a strip which is propelled by tractive force applied to the strip only after it has "set" and the strip, while still plastic, is supported in a flat and approximately horizontal 100 position.

3. Process as in claim 1, in which the strip is plastic while supported in a flat and approximately horizontal position for a sufficient 105 time to enable it to assume a flat form.

4. Process as in claim 2 in which the edges of the pool are maintained hotter than the central portion.

5. Process for producing a continuous 110 strip of glass in which molten glass is rolled into a strip which issues from the rolling apparatus in a direction inclined to the horizontal and is deflected into an approximately horizontal and flat position by tractive force 115 applied to the strip only after it has "set", the strip being supported before it has "set" in the flat and approximately horizontal position.

6. Process for producing a continuous strip of glass in which molten glass issuing from a tank to form a pool, is rolled into a strip which issues from the rolling apparatus in a direction inclined to the horizontal and is deflected into an approximately horizontal 125 and flat position by tractive force applied to the strip only after it has "set", the strip being supported in the flat and approximately horizontal position while still plastic.

7. Process as in claim 6 in which the edges 130

of the pool are maintained hotter than the central portion.

8. Process for producing a continuous strip of glass in which molten glass is rolled into a strip which is propelled by tractive force applied to the strip only after it has "set", the strip being supported before it has "set" in a flat and approximately horizontal position and the loss of heat from the strip 10 while in the said position being controlled so that the strip is "set" only just before the point where the tractive force is applied.

9. Process for producing a continuous strip of glass in which molten glass issuing 15 from a tank to form a pool, is rolled into a strip which is propelled by tractive force applied to the strip only after it has "set" and the strip while still plastic is supported in a flat and approximately horizontal position, the loss of heat from the strip while 20 in the said position being controlled so that the strip is "set" only just before the point where the tractive force is applied.

10. Apparatus for producing a continuous strip of glass by rolling molten glass, comprising in combination, a rolling apparatus, a flat and approximately horizontal bed of such length that the strip is "set" before reaching the end of the bed remote from the 25 rolling apparatus, means acting on a part of the strip which has "set" and adapted to apply tractive force to the length of strip extending from the said means to the rolling apparatus and to draw the strip continuously 30 over the bed.

11. Apparatus for producing a continuous strip of glass by rolling molten glass, comprising in combination, a tank, a rolling apparatus, a conduit to lead the glass from the tank to the rolling apparatus, a flat and approximately horizontal bed of such length that the strip is "set" before reaching the end of the bed remote from the rolling apparatus, means acting on a part of the strip 40 which has "set" and adapted to apply tractive force to the length of strip extending from the said means to the rolling apparatus and to draw the strip continuously over the bed.

12. Apparatus for producing a continuous strip of glass by rolling molten glass, comprising in combination, a rolling apparatus, a flat and approximately horizontal bed located so close to the rolling apparatus that the strip is plastic while on the bed, and of such length that the strip is "set" before reaching the end of the bed remote from the rolling apparatus, means acting on a part of the strip which has "set" and adapted to 50 apply tractive force to the length of strip extending from the said means to the rolling apparatus and to draw the strip continuously over the bed.

13. Apparatus for producing a continuous strip of glass by rolling molten glass,

comprising in combination, a tank, a rolling apparatus, a conduit to lead the glass from the tank to the rolling apparatus, a flat and approximately horizontal bed located so close to the rolling apparatus that the strip is plastic while on the bed, and of such length that the strip is "set" before reaching the end of the bed remote from the rolling apparatus, means acting on a part of the strip which has "set" and adapted to apply tractive force to the length of the strip extending from the said means to the rolling apparatus and to draw the strip continuously over the bed.

14. Apparatus for producing a continuous strip of glass by rolling molten glass, comprising in combination, a rolling apparatus, a stationary bed consisting of a curved portion followed by a flat and approximately horizontal portion of such length that the strip is "set" before reaching the end of the bed remote from the rolling apparatus, means acting on a part of the strip which has "set" and adapted to apply tractive force to the length of strip extending from the said means to the rolling apparatus and to draw the strip continuously over the bed.

15. Apparatus for producing a continuous strip of glass by rolling molten glass, comprising in combination, a tank, a rolling apparatus, a conduit to lead the glass from the tank to the rolling apparatus, a stationary bed consisting of a curved portion followed by a flat and approximately horizontal portion of such length that the strip is "set" before reaching the end of the bed remote from the rolling apparatus, means acting on a part of the strip which has "set" and adapted to apply tractive force to the length of strip extending from the said means to the rolling apparatus and to draw the strip continuously over the bed.

16. Apparatus for producing a continuous strip of glass by rolling molten glass, comprising in combination, a rolling apparatus, a stationary bed consisting of a curved portion followed by a flat and approximately horizontal portion, the latter portion being located so close to the rolling apparatus that the strip is plastic while on the bed, and of such length that the strip is "set" before reaching the end of the bed remote from the rolling apparatus, means acting on a part of the strip which has "set" and adapted to apply tractive force to the length of strip extending from the said means to the rolling apparatus and to draw the strip continuously over the bed.

17. Apparatus for producing a continuous strip of glass by rolling molten glass, comprising in combination, a tank, a rolling apparatus, a stationary bed consisting of a curved portion followed by a flat and approximately horizontal portion, the latter portion being located so close to the rolling

- apparatus that the strip is plastic while on the bed, and of such length that the strip is "set" before reaching the end of the bed remote from the rolling apparatus, means 5 acting on a part of the strip which has "set" and adapted to apply tractive force to the length of strip extending from the said means to the rolling apparatus and to draw the strip continuously over the bed.
- 10 18. Apparatus for producing a continuous strip of glass by rolling molten glass, comprising in combination, a tank, a rolling apparatus, a conduit for bringing molten glass from the tank to the rolling apparatus, 15 passages in the side walls of said conduit, means supplying heat in the said passages, a flat and approximately horizontal stationary bed and means adapted to draw the strip continuously over the bed.
- 20 19. Apparatus for producing a continuous strip of glass by rolling molten glass, comprising in combination, a tank, a rolling apparatus, a conduit for bringing molten glass from the tank to the rolling apparatus, 25 passages in the side walls of said conduit, means supplying heat in the said passages, a stationary bed consisting of a curved portion followed by a flat and approximately hori-
- zontal portion, so long that the strip is "set" before reaching the end of the bed remote 30 from the rolling apparatus and means adapted to draw the strip continuously over the flat portion of the bed and keep it normally out of contact with the curved portion thereof. 35
20. Apparatus for producing a continuous strip of glass by rolling molten glass, comprising in combination, a tank, a rolling apparatus, a conduit for bringing molten glass from the tank to the rolling apparatus, 40 passages in the side walls of said conduit, means supplying heat in the said passages, a stationary bed consisting of a curved portion followed by a flat and approximately horizontal portion, the said flat portion being 45 located so close to the rolling apparatus that the strip is "set" before reaching the end of the bed remote from the rolling apparatus, and means adapted to draw the strip 50 continuously over the flat portion of the bed and keep it normally out of contact with the curved portion thereof.

In testimony whereof I have affixed my signature hereto.

ERNEST BRISTOW LE MARE.
